US00D854330S

(12) **United States Design Patent** (10) Patent No.: **US D854,330 S**
 Courtney et al. (45) Date of Patent: ** Jul. 23, 2019

(54) **DENTAL APPLIANCE**(71) Applicant: **Dyson Technology Limited**, Wiltshire (GB)(72) Inventors: **Stephen Benjamin Courtney**, Bath (GB); **Timothy Nicholas Stickney**, Gloucester (GB); **Thomas James Dunning Follows**, Swindon (GB); **William John Bex-Russell**, London (GB); **Jonathan George Marsh**, Swindon (GB); **Adam James Bates**, Oxford (GB); **Peter David Gammack**, Gloucester (GB)(73) Assignee: **Dyson Technology Limited**, Malmesbury, Wiltshire (GB)(**) Term: **15 Years**(21) Appl. No.: **29/602,379**(22) Filed: **May 1, 2017**(30) **Foreign Application Priority Data**

Nov. 2, 2016 (GB) 6002226
 Nov. 2, 2016 (GB) 6002231
 Nov. 2, 2016 (GB) 6002236

(51) LOC (11) Cl. **04-02**

(52) U.S. Cl.

USPC ..... **D4/101**(58) **Field of Classification Search**

USPC D4/100, 101, 102, 104, 105, 106, 107, D4/108, 109, 110, 111, 112, 113, 114, D4/115, 116, 117, 118, 119, 120, 121, D4/122, 123, 124, 125, 126, 127, 128, D4/129, 130, 132, 133, 134, 136, 138, D4/199; D24/111, 127, 152, 177

CPC A46B 11/0062; A46B 13/04; A46B 2200/1066; A46B 11/00; A46B 13/00; A46B 15/0097

CLAIM

We claim the ornamental design for a dental appliance, as shown and described.

DESCRIPTION

FIG. 1 is a perspective view of a dental appliance showing our new design;

FIG. 2 is a front elevation view thereof;

FIG. 3 is a rear elevation view thereof;

FIG. 4 is a side elevation view thereof;

FIG. 5 is a side elevation view of the opposite side of the design as that shown in FIG. 4;

FIG. 6 is a top plan view thereof;

FIG. 7 is a bottom plan view thereof;

FIG. 8 is a perspective view of another embodiment of a dental appliance showing our new design;

FIG. 9 is a front elevation view thereof;

FIG. 10 is a rear elevation view thereof;

FIG. 11 is a side elevation view thereof;

FIG. 12 is a side elevation view of the opposite side of the design as that shown in FIG. 11;

FIG. 13 is a top plan view thereof; and,

FIG. 14 is a bottom plan view thereof.

The broken lines shown in the drawings illustrate portions of a dental appliance that form no part of the claimed design.
